(No Model.)

R. B. A. KNOP.
PAIL.

No. 513,269.

Patented Jan. 23, 1894.

Fig. 1.

UNITED STATES PATENT OFFICE.

RHINEHARD B. A. KNOP, OF MILWAUKEE, WISCONSIN.

PAIL.

SPECIFICATION forming part of Letters Patent No. 513,269, dated January 23, 1894.

Application filed April 22, 1893. Serial No. 471,381. (No model.)

To all whom it may concern:

Be it known that I, RHINEHARD B. A. KNOP, a citizen of the United States, and a resident of Milwaukee, in the county of Milwaukee, 5 and in the State of Wisconsin, have invented certain new and useful Improvements in Pails; and I do hereby declare that the following is a full, clear, and exact description thereof.

My invention has for its object to provide 10 a pail capable of being collapsed and folded into small compass when not in use, and it consists in certain peculiarities of construction and combination of parts hereinafter described with reference to the accompanying 15 drawings and subsequently claimed.

In the drawings: Figure 1 represents a vertical section of a pail constructed according to my invention in condition for use, and Fig. 2 a horizontal section of the same taken on 20 line 2-2 of the preceding figure.

Referring by letter to the drawings, A represents the bottom of my pail, this bottom being of sheet-metal or other suitable material provided with a vertical flange *b* of any suitable height. As herein shown the flange has 25 its upper portion folded on itself in such a manner as to form an annular recess *c* in which the lower edge of an endless web of water-proof canvas or other pliable water- 30 proof material *B* is clamped. The endless web of pliable material is shown as having its upper edge clamped in a depending annularly recessed portion *d* of a sheet-metal top *C*, the latter in this instance having a 35 hinged section *D* held closed by a spring-snap *e* or other suitable means, and said cover has a downwardly extended flange *f* of such dimensions as to inclose and fit snug against the bottom flange *b* when the pail is collapsed.

40 To the top-flange *f* I prefer to connect a bail *E* as shown in Fig. 1.

While the pail as thus far described is shown as having a circular bottom, wall and top it may be of any other desirable contour 45 without departure from my invention.

Pivotaly connected to the pail-bottom *A* upon its inner face and on opposite sides of the center adjacent to the flange *b* are the lower members *F* of hinges that have their 50 upper members *G* likewise connected to the inner face of the pail-top, the joint of each

hinge being about midway of the length of the pail when the latter is in condition for use, and by the extension of the hinges the pliable portion of the pail is made taut. The 55 lower hinge-members *F* are provided with eyes *g* through which run flexible devices *H* connecting the pail-bottom and a transverse brace *I*, the latter being in the form of a hinge having the outer extremities of its members 60 preferably of such shape as to straddle the aforesaid hinge-members, and ears *h* arranged in pairs on the brace serve as stops to prevent disengagement of the same from said hinge-members when the pail is collapsed in 65asmuch as these hinge-members fold down between the stops.

Connecting the central portion of the brace with the pail-bottom is a spring *J* expanded incidental to the elevation of said brace (when 70 the hinges that join the bottom and top of the pail are straightened out) to thereby exert power sufficient to prevent buckling of the aforesaid brace under ordinary circumstances.

The hinges formed by the members *F*, *G*, 75 are of a trifle less length than a measurement equal to the diameter of the pail in order that they may close and abut against each other within the limits of said pail and to effect this result it is necessary to first pull up 80 the center of the brace *I* against the power of the spring *J* thereby permitting said hinge members to swing inward on their pivots. As the hinges close up, the retraction of the 85 spring will cause the brace to run down the necessary distance and the pliable portion of the pail-wall being properly tucked in, the top of my device will close on the bottom thereof to thereby confine the several parts in the smallest possible space. 90

The pail herein described is especially designed for the receptacle in which to carry live bait for fishermen, and because of its being collapsible it may be more conveniently carried than such pails as ordinarily constructed. 95

Having thus described my invention, what I claim as new, and desire to secure by Letters Patent, is—

1. A collapsible pail comprising a non-pliable bottom provided with an upwardly extended flange, a top of like material having a 100

downwardly extended flange of such dimensions as to inclose and fit snug against the bottom flange when the pail is collapsed, an endless web of pliable material joined to said flanges, hinges connecting the bottom and top, and suitable means for maintaining the hinges in extended position, substantially as set forth.

2. A collapsible pail comprising a bottom and top of suitable non-pliable material, the top having a hinged section and means for holding the same in a closed position, an endless web of suitable pliable material intermediate of the top and bottom, hinges connecting said top and bottom, and suitable means for maintaining the hinges in extended position, substantially as set forth.

3. A collapsible pail comprising bottom and top sections of suitable non-pliable material, an intermediate endless web of suitable pliable material, hinges connecting the bottom and top sections, a jointed spring-controlled brace having its extremities of such form as to loosely engage with the lower-hinge-members, guides on the lower hinge-members, and flexible devices that work loose in the guides,

and connect with the brace and pail-bottom, substantially as set forth.

4. A collapsible pail comprising bottom and top sections of suitable non-pliable material, an intermediate endless web of suitable pliable material, hinges connecting the bottom and top sections, a jointed spring-controlled brace having its extremities of such form as to loosely engage with the lower hinge-members, guides on these lower hinge-members flexible devices that work loose in the guides and connect with the brace and pail-bottom, a spring that also connects said brace and pail-bottom, and ears at opposite sides of the brace members adjacent to their extremities, substantially as set forth.

In testimony that I claim the foregoing I have hereunto set my hand, at Milwaukee, in the county of Milwaukee and State of Wisconsin, in the presence of two witnesses.

RHINEHARD B. A. KNOP.
